UNITED STATES PATENT OFFICE.

FREDERICK LANE, OF BOSTON, MASSACHUSETTS, ASSIGNOR TO OSCAR GASSETT, OF SAME PLACE.

APPARATUS FOR BURNING LIQUID FUEL.

SPECIFICATION forming part of Letters Patent No. 333,311, dated December 29, 1885.

Application filed June 1, 1885. Serial No. 167,209. (No model.)

To all whom it may concern:

Be it known that I, FREDERICK LANE, residing in Boston, county of Suffolk, State of Massachusetts, have invented an Improvement 5 in Apparatus for Burning Liquid Fuel, of which the following description, in connection with the accompanying drawings, is a specification, like letters on the drawings representing like parts.

10 My invention relates to an apparatus for burning liquid fuel—such, for instance, as petroleum and the various hydrocarbon derivatives therefrom, or other combustible oils or liquids—and is embodied in an apparatus of that class in which the flame is employed to generate steam, which is delivered in a jet 15 into the flame of the burning liquid, combining therewith and producing perfect combustion and intense heat.

20 The apparatus is adapted to be applied to a cooking stove or range of ordinary construction without material change in the arrangement of the stove, and the invention is applicable to any of the uses for which furnaces or heaters are commonly employed. In apparatus of this class as heretofore made it is difficult to maintain the proper proportions 25 between the steam and the liquid fuel so as to afford perfect combustion; and the present invention consists, essentially, in means for automatically governing the effect of the flame on the steam-generator, and also for automatically controlling the supply of water to the steam-generator, so that the proper amount of 30 steam is generated for the amount of oil or liquid fuel at each moment supplied. The flame and heat produced by the apparatus may consequently be governed merely by regulating the amount of liquid fuel supplied, and the 35 supply of water and generation of steam will take care of itself. The flame is produced in a movable burner, in this instance shown as a tube having an opening through which the flame issues to act on the boiler or steam-generator, and means are provided for changing 40 the position of the said burner in accordance with the pressure of steam in the generator, so that the flame is thrown more or less directly against the steam-generator in

accordance as the pressure in the latter falls 50 or rises, thus maintaining the pressure substantially uniform, or in the proper proportion to the amount of fuel at any time being consumed.

The steam-generating apparatus comprises 55 a tight receptacle or boiler, into which the water is fed, and a superheating chamber, which receives the steam from the said boiler, and from which it is delivered in a dry superheated condition to the burner tube, 60 and the said boiler is itself movable, rising and falling as the weight of its contents diminishes or increases; and the boiler is connected with a valve controlling the flow of water from the reservoir or supply into the 65 boiler. This valve is operated by the rise and fall of the boiler, being closed in proportion as the boiler sinks by the increased weight of the water within it, so that the water cannot rise above a definite predetermined 70 level in the boiler, and is automatically maintained at the proper level while the apparatus is in operation.

Figure 1 is a front elevation of a stove provided with apparatus for burning liquid fuel 75 embodying this invention; Fig. 2, a detail showing the valve controlling the supply of water to the steam-generator and the mechanism for operating the said valve; Fig. 3, an end elevation of the apparatus inside the stove, 80 as seen looking from the left in Fig. 1; Fig. 4, a transverse vertical section thereof; Fig. 5, an end elevation of the apparatus inside the stove, as viewed from the right hand in Fig. 1; Fig. 6, a plan view of a portion of the 85 steam-generating apparatus, and Fig. 7 a longitudinal section of a portion of the burner on a larger scale.

The fuel-burning apparatus may be of any suitable size and shape, according to the purpose for which it is intended, being shown in this instance as properly constructed to enter the fire-chamber of a stove or range, A, of usual construction, having an elongated rectangular fire-chamber, the usual grate being 90 removed and the fuel-burning apparatus occupying the space commonly occupied by both the fire-chamber and ash-pit of the stove. 95

The fuel-burning apparatus is shown as supported on two uprights, a a' , and comprises a burner, b , shown in this instance as tubular in form and provided at one end with a fuel-chamber, b' , containing fragments of fire-brick or other refractory material in a divided state, as shown at b^2 , Fig. 7, upon which the liquid fuel is delivered, being, as shown in this instance, discharged from a tube, c , and falling o drop at a time or in a small stream upon the said fragmentary material, which serves to divide it, or, in other words, operates somewhat as a lamp-wick to facilitate the burning of the said fuel. The delivery-pipe c is connected 5 with a reservoir, d , (see Fig. 1,) for the liquid fuel, which reservoir is preferably contained within a reservoir, e , for water, which is delivered through a pipe, f , to the steam-generator g , consisting in this instance of a tubular o case or shell connected by suitable bars, g' , with the superheating-chamber h , which communicates with the boiler or steam-generator g by a pipe, h' , leading from the upper part of the generator g , so that the steam will be 50 conveyed from the said generator g to the superheater h , in which it will be superheated, so that it may be delivered from the said chamber h in a thoroughly dry condition through a suitable pipe, i , (best shown in Fig. 7,) o terminating in a nozzle or jet-piece, i' , directed toward the interior of the burner or flame tube b , which is provided with an outlet, b^3 , shown as a longitudinal slot, from which the flame is directed toward the boiler and 55 superheating-chamber, as best seen in Fig. 4, impinging more directly on the latter, although a sufficient portion of heat is imparted to the generator g to maintain the proper generation of steam therein.

o The parts thus far described, broadly considered, are not of my invention, and are not herein claimed, except in connection with details of construction and arrangement hereinafter described.

15 It is necessary in order to produce steady and uniform combustion that the pressure in the steam-generating apparatus should be maintained at the proper point, and if the generation of steam is too rapid, so that its pressure rises, the heat applied to the generator should be reduced, and, on the other hand, if the pressure falls, more heat should be applied to the generator. In order to automatically regulate the application of heat to the 20 generator so as to maintain the pressure always at the proper point, the burner b is made movable, being shown in this instance as mounted on rollers b^4 , so that it can turn easily about its axis, in order to throw the flame issuing from 25 the opening b^3 more or less directly toward the generator g , and the burner is thus turned by mechanism governed in its operation by variations in pressure in the boiler or generator g . This mechanism, which regulates the effect of 30 the burner on the steam-generator, comprises a pipe, k , leading from the upper part of the

boiler to a chamber, k' , shown in this instance as of bellows-like construction, consisting of a number of flexible disks or diaphragms, which may be of thin sheet metal alternately united 70 at their edges and at central openings, so that an increase in pressure in the said chamber will tend to expand it or move the extreme diaphragms or disks away from one another, and a diminution in pressure will permit the 75 chamber to contract under the action of a suitable force acting in opposition to the internal pressure, said force being supplied in this instance by a weight, k^2 . (See Figs. 1 and 4.) This construction of the pressure-chamber is 80 adopted, as it is capable of responding to extremely small variations in pressure, although it is obvious that the steam from the boiler might act on a piston or a single diaphragm, or any suitable or usual device that can be 85 readily moved by the pressure of the steam exerted upon it. The lower disk of the chamber k' is stationary, and the upper disk or top of the said chamber, which is moved with relation to the lower disk by changes in internal 90 pressure, as just described, is connected by a rod, k^3 , with a lever, k^4 , pivoted at one end upon one of the frame-plates a' , or a stationary projection therefrom, and connected at its other end by a link, k^5 , with an arm, k^6 , (see 95 Fig. 4,) projecting from one side of the burner b , so that as the upper plate of the chamber k' rises and falls the burner is rolled about its axis, turning the opening b^3 farther away from or more nearly toward the boiler g , according 100 to as the pressure rises or falls in the latter, and in actual operation the burner will find a position at which just the proper amount of heat is applied to the boiler to maintain the pressure therein substantially constant and of proper 105 amount to produce a jet of steam issuing from the nozzle i' which will properly combine with the liquid fuel at that time supplied to the burner. It is also necessary to regulate the supply of water to the boiler so that it will 110 at all times be substantially equal to the amount drawn out in the form of steam at the nozzle i' , since, if a smaller supply were provided, the boiler might become empty or an insufficient amount of steam be generated to maintain 115 perfect combustion, or, if the supply were too great, the boiler might fill, so that water would enter the superheater, and the jet delivered at the nozzle i' would contain particles of water or vapor, instead of dry steam, and 120 would thus cause sputtering or imperfect combustion in the burner.

In order to regulate the supply of water and increase it when the water falls in the boiler, and diminish or wholly cut it off when it rises 125 above the proper level in the boiler, the said boiler is made movable and free to rise and fall as the weight of water within it diminishes or increases, the frame-work g' , connecting the boiler and superheater, being, as shown in this 130 instance, pivoted upon the frame-plate a' , so that they just about counterbalance one an-

other when the proper amount of water is in the boiler, the superheater or a suitable counter-weight overbalancing and raising the boiler when it contains a less amount of water, and 5 being overbalanced by it when containing a greater amount of water.

The inlet-pipe *m*, leading to the boiler, (see Fig. 2,) passes through a slot, *m*², in the end of the stove and in the frame-work *a*, (see Fig. 10 5,) which accommodates the movement of the boiler about its pivot, and is connected by a flexible pipe, *m*³, with the pipe *f*, leading from the water-reservoir, the said pipe containing a cock or valve, *f*', (see Fig. 2,) the handle of 15 which is connected by a link, *o*, with an arm, *o*', leading from the pipe *m* or from some part of the movable frame-work which supports the boiler, in such manner that as the boiler rises it opens the said valve, admitting a larger 20 supply of water to the boiler, and as the boiler sinks it closes the said valve or reduces the supply of water to the boiler, and will finally wholly cut off the said supply in case the boiler sinks a sufficient amount, as will take place if 25 the water rises above the predetermined level therein.

In operation the boiler will assume a certain level at which the valve will be opened sufficiently to supply the water just as fast as 30 it is withdrawn in the form of steam, which will depend upon the amount of fuel at any moment being consumed. It is necessary, therefore, in order to regulate the fire or heat produced by the apparatus, merely to control 35 the amount of liquid fuel supplied to the burner through the pipe *c*, leading from the reservoir *d*, which pipe contains a controlling cock or valve, *c*', and preferably a sight-feed tube, *c*², through which the falling drops or 40 stream of oil or liquid fuel may be observed. The reservoir *d* preferably contains a strainer or filter, *d*', to prevent particles of sedimentary matter from entering the pipe, and thus interfering with the operation of the valve *c*'. 45 If desired to increase the fire or heat produced, more fuel is permitted to enter, and if the generation of steam then becomes too rapid the burner will automatically turn so as to direct the flame somewhat farther away from 50 the boiler, but at the same time the pressure will be somewhat increased, and there will consequently be a larger delivery of steam from the nozzle *i*', sufficient to combine with the increased amount of fuel, and this increased consumption of steam will draw from the boiler, lightening the same so that it will sink and open the valve *f*' further, and thus afford a correspondingly-increased supply of water; and in 55 actual practice the appliances herein described for regulating the effect of the flame upon the steam-generator and the supply of water thereto will operate automatically to produce at any moment a jet of steam corresponding in amount to the amount of fuel at 60 that time supplied, so that the proper combustion will be maintained without care or

skill on the part of an attendant, who merely has to supply the amount of fuel at any time needed to produce the heat required. The pipe *k*, leading from the boiler to the burner-regulating chamber *k*', may either be made 70 flexible or, as shown in this instance, provided with a swivel-joint, *k*⁶, (see Fig. 6,) in the axis of oscillation of the boiler and connected superheating-chamber, to accommodate 75 the movement of the said boiler and chamber. The end of the burner is provided with an opening, *b*⁵, (see Figs. 5 and 7,) which admits air in proper quantity to support combustion, and the oil and steam pipes *c* and *i* 80 preferably enter this opening, as shown, near the central line of the burner, so that its movement does not materially change its position with relation to the said pipes.

The movement of the superheater in connection with the boiler is not sufficient to materially change the position of the steam-nozzle *i*' in the burner, the said nozzle usually being near the center line of the burner; but it is obvious that, if the relation of the burner 90 and superheater were such as to require it, a flexible or jointed connection might be made in the pipe *i*', to accommodate the movement of the superheater without changing the position of the nozzle *i*' with relation to the 95 burner; or the superheating-chamber itself might be stationary and the pipe connecting it with the boiler made flexible or jointed, in which case the boiler would be counterbalanced by a weight provided for that purpose, 100 instead of by the superheater.

An air-pipe, *p*, and forcing apparatus *p*' are provided in order to direct the flame through the burner-tube and out of the opening *b*' in starting the apparatus until the flame thus 105 issuing generates steam in the steam-generator, after which the operation will be continuous and automatic as long as fuel is supplied.

I claim—

1. An apparatus for burning liquid fuel, comprising a steam-generator and movable burner, the position of which with relation to the steam-generator is dependent on the pressure in the said generator, substantially 115 as described.

2. The combination, with a burner for liquid fuel, of a boiler or steam-generator which supplies a jet of steam to the said burner, and is movable by the weight of the contained 120 liquid, and a feed-pipe, the flow of fluid through which to the boiler is governed by the movement of the latter, substantially as described.

3. The combination of a movable burner 125 and steam generator or boiler receiving heat therefrom with a pressure-chamber communicating with the said boiler, and connecting mechanism which varies the position of the burner in accordance with variations in pressure in the said chamber and boiler, substantially as and for the purpose set forth.

4. In an apparatus for burning liquid fuel, a movable burner and a movable boiler, the position of the burner depending on the pressure in the boiler, and the feed or supply of water to the boiler depending on its position, substantially as described.

5. A burner for liquid fuel, having an outlet for flame or heated gases, combined with a steam generator or boiler heated thereby, and mechanism, controlled by the pressure in the boiler, by which the position of the burn-

er-outlet with relation to the boiler is varied, substantially as and for the purpose described.

In testimony whereof I have signed my name to this specification in the presence of two subscribing witnesses.

FREDERICK LANE.
